FOOD TONGS OR THE LIKE

Arthur G. Bruns, 627 Eldron Drive, Miami Springs, Fla.

Filed Feb. 23, 1965, Ser. No. 83,921

Term of patent 14 years

(Cl. D44—4)

FIGURE 1 is a perspective view of food tongs or the like showing my new design;

I claim:

The ornamental design for food tongs or the like, substantially as shown and described.
